UNITED STATES PATENT OFFICE.

DONALD FERGUSON, OF CHATFIELD, MINNESOTA.

CAN CLOSURE.

Application filed February 7, 1921. Serial No. 443,135.

To all whom it may concern:

Be it known that I, DONALD FERGUSON, a citizen of the United States, residing at Chatfield, in the county of Fillmore and State of Minnesota, have invented certain new and useful Improvements in a Can Closure, of which the following is a specification.

This invention relates to closures for cans 10 and the like and more particularly to oil cup closures.

The object of the invention is to provide a simple and efficient closure of this character which may be quickly opened or closed by a 15 partial turn in one direction or the other of a rotary member having arcuate closing plates or shutters attached thereto at one end, their other ends being mounted to slide radially in guides leading from the opening 20 controlled by the closure.

Another object is to so construct the shutter plates and co-operating elements that they may be cheaply manufactured and which form a closure thoroughly effective to 25 shut out dust and the like from the container of which it forms a part.

With these and other objects in view, the invention consists in certain novel features of construction as hereinafter shown and described and then specifically pointed out in the claims, and in the drawings illustrative of the preferred embodiment of the invention.

Figure 1 represents a central vertical section of the closure constituting this invention.

Fig. 2 is a transverse section taken on the line 2-2 of Fig. 1.

Fig. 3 is a front or top plan view of the 40 closure with the shutters or plates in closed operative position.

Fig. 4 is a view similar to Fig. 2 with the shutters in closed position, and

Fig. 5 is a horizontal section with the 45 shutters removed showing the slotted base plate in plan view.

In the embodiment illustrated, the closure constituting this invention is shown mounted in a container indicated at C having a flanged opening O to receive the closure. The closure comprises a cup-shaped member 1, having a laterally and outwardly extending flange 2, at the top thereof. The inner end of the member 1, is extended and cylind-

rical in contour, as at 5, and formed integral with the cylindrical portion 5, is the bottom 3, of the member 1. The cylindrical portion 5, of the member 1, is snugly fitted within the opening O, of the container, and the closure is employed for opening and closing the said opening O. The bottom 3, of the member 1, is provided with a centrally disposed opening surrounded by an annular flange 4, formed integral with the inner face of the bottom 3. Mounted against the outer face of the bottom 3, of the member 1, and arranged within the cylindrical portion 5, is a plate 6, the latter corresponding in thickness to the depth of the cylindrical portion 5. This plate 6 has a central opening 7 of the same shape and size as the opening in the bottom 3 of the member 1 and registers therewith at all times. This plate 6 may be secured within the member 1 by shrinking or in any other suitable manner, and is provided with a plurality of radially extending slots 8 leading from said opening and terminating adjacent the perimeter of the plate. Three of these slots are here shown, spaced equal distances apart and are designed to co-operate with three shutter plates 10 which are made arcuate in form and operate in a manner presently to be described. These plates or shutters 10 are of a width substantially the same as the distance between the perimeter of the plate 6 and the wall of the opening therein so that when said plates are in their full open position, as shown in Fig. 2 the inner edges will substantially register with the walls of the 90 openings in plate 6 and bottom 3 respectively.

The arcuate plates 10 are preferably rounded at their ends and at one end are provided with lugs 11, and at the other end with L-shaped fingers 12. The lugs 11, extend in opposite directions with respect to the fingers. The lugs 11 are designed to enter and slide in the slots 8 which form guides for the plates 10 when moved into 100 open or closed position by means presently to be described.

A shutter actuating member 13 shown in the form of a bowl or cup provided at its outer edge with an outwardly extending in-turned flange 14 adapted to be crimped around the flange 2 of the member 1, as is shown clearly in Fig. 1 forming a pocket to

house the flange 2 which forms a guide for the member 13 which is adapted to be rotated in opposite directions in said member 1 for opening and closing the shutters 10, 5 as now to be described.

This cup shaped member 13 has a central opening 16 in the bottom 15 thereof of a size and shape corresponding to the openings in bottom 3 of the member 1 and the 10 plate 6 mounted therein so that when the parts are assembled these three openings will register. The bottom 15 of the member 13 is provided with three apertures 17 therein spaced equal distances apart and which 15 are designed to receive the fingers 12 of the shutters 10 which are passed through said apertures and bent over against the inner face of said bottom 15, as is shown clearly in Figs. 1 and 3 and by means of which the 20 actuating member 13 is connected with the shutters at the ends thereof opposite to those which are engaged with the guides or slots 8 in plate 6. When the parts are assembled, the arcuate plates 10 are mounted with one 25 end engaged with the slots 8 and the other end lapping the slot engaged end of the adjacent plate, as is shown clearly in Fig. 2, and when in open position are arranged as 30 shown in said figure in the form of a circle, the central opening of which corresponds to the openings of the members 3, 6 and 15 thereby affording access to the interior of the container C for the insertion or removal of the contents.

35 The cup-shaped member 13 being rotatable within the bowl shaped member 1 and connected at its bottom with the arcuate plates 10 will when partially turned in one direction or the other open or close said 40 plates according to the direction in which it is turned. If turned toward the left the opening is as shown in Fig. 2, while if turned toward the right will close them as 45 shown in Fig. 4. It will thus be seen that a closure constructed as herein shown and described may be quickly opened or closed by a simple partial turn of the member 13 so that ready access may be had to the interior of the container, which may be either an oil 50 cup or any other receptacle designed to be equipped with a closure of this character.

By constructing the plates 10 of thin sheet metal and bending the tips of the ends thereof in opposite directions to form pins 55 for connecting them with the guides 8 and with the actuating member 13 produces a very cheap structure and yet one which will be thoroughly effective in connecting the plates in the manner desired.

60 The preferred embodiment of the invention is disclosed in the drawings and set forth in the specification, but it will be understood that any modifications within the scope of the claimed invention may be made 65 in the construction without departing from

the principle of the invention or sacrificing any of its advantages.

I claim:

1. A closure for liquid containers comprising a cup-shaped member having a cylindrical lower portion formed with a bottom provided with an opening, an apertured plate seated in said cylindrical inner portion and formed with radially disposed slots, a cup-shaped element mounted in and shiftably connected with said member and having an opening at its bottom registering with the opening in said plate and bottom of said member, the bottom of said element spaced from said plate, and a series of arcuate overlapping shutters arranged between said element and plate and each having one end provided with a lug, and its other end with a finger, said lugs slidably mounted in said slots and said fingers connected to the bottom of said element. 70

2. A closure for liquid containers comprising a cup-shaped member having a cylindrical inner portion provided with a bottom formed with an opening, an apertured plate seated in said inner cylindrical portion and formed with radially disposed slots, a cup-shaped element mounted in said member and having an opening in its bottom registering with the opening in said plate 90 and said member, the bottom of said element spaced from said plate, a series of arcuate overlapping shutters arranged between said element and plate and each having one end provided with a lug and its other end provided with a finger, said lugs shiftably mounted in said slots and said fingers connecting the shutters at the bottom of said element, and said member and element having inherent means for shiftably connecting 95 the element to the member. 100

3. A closure for liquid containers comprising a cup-shaped member having a cylindrical inner portion provided with a bottom formed with an opening, an apertured 110 plate seated in said inner cylindrical portion and formed with radially disposed slots, a cup-shaped element mounted in said member and having an opening in its bottom registering with the opening in said plate 115 and said member, the bottom of said element spaced from said plate and provided with a series of apertures, a series of arcuate overlapping shutters arranged between said element and plate and each having one end provided with a lug and its other end with an L-shaped finger, said lugs shiftably mounted in said slots and said fingers extending through the apertures in the bottom 120 of said element and further overlapping 125 said bottom.

In testimony whereof, I affix my signature hereto.

DONALD FERGUSON.
